UNITED STATES PATENT OFFICE.

WILLIAM S. BEEMAN, OF ASHLAND, WISCONSIN.

INTERMITTENT GRIP FOR SAW-MILL SET-WORKS, &c.

SPECIFICATION forming part of Letters Patent No. 425,398, dated April 15, 1890.

Application filed April 22, 1889. Serial No. 308,174. (No model.)

To all whom it may concern:

Be it known that I, WILLIAM S. BEEMAN, of Ashland, in the county of Ashland and State of Wisconsin, have invented certain new and useful Improvements in Intermittent Grips for Saw-Mill Set-Works, &c.; and I do hereby declare that the following is a full, clear, and exact description of the invention, which will enable others skilled in the art to which it pertains to make and use the same, reference being had to the accompanying drawings, and to the letters of reference marked thereon, which form a part of this specification.

The main object of my invention is to provide a simple and effective substitute for a pawl and ratchet-wheel in a saw-mill set-works and for the various uses to which a pawl and ratchet-wheel are applicable.

It consists, essentially, of an intermittent grip composed of an internal friction-wheel, an oscillatory head, friction-shoes, and mechanism interposed between said shoes and head, whereby the said shoes are forced outwardly into engagement with said friction-wheel when the head is turned forward, but are released from such engagement when the head is turned backward, and of certain other peculiarities of construction and arrangement, hereinafter specifically described, by which said grip is adapted to a saw-mill set-works or the like.

In the accompanying drawings like letters designate the same parts in the several figures.

Figure 1 is a vertical cross-section of a portion of a saw-mill carriage to which my improved intermittent grip is applied. Fig. 2 is a side elevation, on a larger scale, of the intermittent grip, the front side plate or cover being removed. Fig. 3 is an axial section on the line $x-x$, Fig. 2, of the clutch on a still larger scale. Fig. 4 is an inside view of one of the side plates or covers of the intermittent grip, showing the device by which the friction-shoes are held out of engagement with the friction-wheel. Fig. 5 is a detail view of the movable bearing for the friction-driver employed with the friction-wheel of the grip for "receding," and Fig. 6 is a plan view of a portion of a saw-mill carriage embodying my improvements.

Although my improved intermittent grip

is applicable to various uses, for convenience of illustration I have shown it adapted and applied to the set-works of a saw-mill carriage. 55

Referring to Figs. 1 and 6, A represents a portion of the frame of a saw-mill carriage; B B, its supporting-axles; C C, the carriage-wheels; D D, the track-rails upon which they travel; E, one of the head-blocks; E', a knee or standard movable longitudinally thereon and provided with a rack e; F, the set-shaft provided with pinions, which engage with racks e of the several knees or standards E', all of the usual or any suitable form and construction.

Upon the set-shaft F is keyed or otherwise suitably fixed a friction-wheel G, which is formed with an overhanging rim g g. Upon the hub of the friction-wheel G are loosely mounted the oscillatory heads H H, which are retained in place thereon by disks g', bolted to and overlapping the outer ends of said hub, as shown in Figs. 2 and 3.

I are friction-shoes adapted on their outer faces to the inner faces of the projecting rim g g of the friction-wheel G and formed on their inner faces with transverse seats for the arms i i, which are interposed between them and the heads H H, in which they have corresponding seats at their opposite ends. The arms i i are set at an inclination to radii of the friction-wheel G, and between them and projections h h on the heads H are interposed springs h', as shown in Fig. 2, which tend to carry their outer ends into the lines of the radii, passing through their inner ends, and thereby to bring the outer faces of the shoes I I into engagement with the rim g g of the friction-wheel G. 90

To the heads H H are bolted or otherwise suitably attached the circular plates or covers J J, which close the annular recesses in the sides of the friction-wheel G. In an annular groove formed in the inner face of each of the plates J J is inserted a ring j, provided with inwardly-projecting studs j', adjacent to the sides of the arms i i, opposite the springs h', as shown in Figs. 2, 3, and 4, and in each of said plates J is journaled a pinion j², which meshes with a rack formed in a portion of the periphery of said ring j. To the outwardly-projecting journal of each pinion j² is fixed a crank-arm j³, carrying at the end a friction-roller j⁴.

k is a rock shaft supported in suitable bearings on the rear side of the carriage parallel with the set-shaft F and provided with the setting-lever K and with a cross-head *k'*, which 5 is connected by links *k²* *k³* with ears *j⁵* *j⁵* on the circular plates J J of the intermittent grip.

K' is a quadrant of the usual form, provided with a fixed and an adjustable stop for limiting the throw of the setting-lever K.

- 10 For the purpose of receding or running the knees back by the movement of the carriage, I provide a shaft *l*, supported in suitable bearings parallel with the set-shaft and provided adjacent to the friction-wheel G with a friction-driver L and with a bevel-gear *l'*, which works with a similar gear *b* on one of the carriage-axles B. Adjacent to the friction-driver L the shaft *l* is supported in an eccentric bearing *l²*, to which is attached a lever *L'*, by means of which the friction-driver L is moved into engagement with the friction-wheel G. To allow the friction-wheel G to turn in the direction opposite that in which it is turned by the friction-shoes I, said shoes 20 must be held out of engagement therewith. To accomplish this end, I provide a forked step-lever N, fulcrumed to the carriage side adjacent to the friction-clutch and having curved arms *n n*, adapted when raised to engage with the friction-rollers *j⁴* on the outer ends of the crank-arms *j³* and thereby turn the rings *j* so as to carry the studs *j'* on their inner faces against the arms *i* and compress the springs *h'*, thus preventing them from 30 forcing the friction-shoes I outwardly into engagement with the rim *g* of the friction-wheel G.

To prevent the overrunning of the friction-wheel G in receding, I provide a brake-strap 40 O, attached at one end to the carriage and at the other end to a bell-crank lever O', by means of which it is drawn by the operator against the periphery of said friction-wheel G.

My improved device operates as follows:

- 45 To advance the knees E', the setting-lever K is swung by the operator to the right or left, or both, and through the cross-head *k'* and links *k²* one of the circular plates J, with the head H attached thereto, is turned forward, 50 and the other circular plate and head H is correspondingly turned backward. When either head H is turned forward, as indicated by the arrow, Fig. 2, the friction-shoes I, thrown outwardly by the action of the springs *h'* on the inclined arms *i* into engagement with the rim *g* of the friction-wheel G, cause said friction-wheel to turn therewith; but when the head H is turned backward the inclined arms *i i* are carried slightly toward the projections 55 *h* against the springs *h'*, and the shoes I are allowed to slide freely along the rim *g* of the friction-wheel without turning it. The distance the knees are advanced by a single throw of the setting-lever is regulated by the 60 adjustable stop in the quadrant K', the lever K being moved in setting from one stop to the other and back to the starting-point. In

case a double throw is given to the setting-lever, the knees will be moved an interval of twice the length produced by a single throw, 70 inasmuch as the movement of the setting-lever in either direction turns the friction-wheel G and set-shaft forward. To run the knees back, the operator depresses the step-lever N, thereby holding the friction-shoes I 75 out of engagement with the rim *g* of the friction-wheel G, as previously described; and when the carriage is being "gigged" or run back, as indicated by the arrow in Fig. 6, the lever *L'* is swung toward the center of the 80 carriage and the continuously-rotated friction-driver L moved into engagement with the periphery of said friction-wheel G, which is thereby turned in the required direction to "recede" the knees. To arrest the backward 85 movement of the knees, the lever *L'* is released and the brake-lever O' moved toward the center of the carriage, carrying the strap O into engagement with the friction-wheel G.

My improved device is susceptible of various modifications within the spirit of my invention to adapt it to the various uses to which it is applicable. For some purposes a single oscillatory head may be employed and the number of friction-shoes may be more or less, according to circumstances. It is obvious that the connections of my improved clutch will be varied according to the uses to which it is applied.

I claim—

1. An intermittent grip consisting of an internal friction-wheel, a friction-shoe adapted to engage the rim of said friction-wheel and having on its inner face a seat, an oscillatory head concentric with said friction-wheel and having a seat in its outer face, and an inclined arm interposed between said head and said shoe and bearing at the ends in the seats therein, substantially as and for the purposes set forth.

2. An intermittent grip consisting of a friction-wheel, friction-shoes adapted to engage the rim of said friction-wheel and having seats in their inner faces, an oscillatory head having seats in its outer face, and inclined arms interposed between said head and said shoes and bearing at the ends in the seats therein, substantially as and for the purposes set forth.

3. An intermittent grip consisting of an internal friction-wheel, friction-shoes adapted to engage the rim of said friction-wheel and having transverse seats in their inner faces, an oscillatory head having similar seats in its outer face, inclined arms interposed between said head and shoes and bearing at the ends in the seats therein, and springs interposed between said arms and projections on said head and tending to force said shoes outwardly into engagement with the rim of said friction-wheel, substantially as and for the purposes set forth.

4. An intermittent grip consisting of an internal friction-wheel, friction-shoes adapted

to engage the inner face of the rim of said wheel, an oscillatory head, inclined arms interposed between said head and shoes, springs interposed between said arms and projections 5 on said head, a plate attached to said head and carrying on its inner face a ring provided with inwardly-projecting studs, and means for turning said ring, whereby said studs are carried into engagement with said 10 arms on the sides opposite said springs, substantially as and for the purposes set forth.

5. An intermittent grip consisting of a friction-wheel having a laterally-projecting rim on both sides, two oscillatory heads, one 15 on each side of said friction-wheel, friction-shoes adapted to engage the overhanging rim of said friction-wheel, inclined arms interposed between said shoes and said heads, and connections whereby said heads are oscillated alternately in opposite directions, substantially as and for the purposes set forth.

6. An intermittent grip consisting of a friction-wheel having a projecting rim on both 25 sides, friction-shoes adapted to engage the inner faces of said rim, oscillatory heads on each side of said friction-wheel and movable independently thereof, inclined arms interposed between said heads and said shoes, 30 cover-plates attached to said heads and inclosing the internal mechanism of said grip, and means for oscillating said cover-plates alternately in opposite directions, substantially as and for the purposes set forth.

35 7. An intermittent grip consisting of a friction-wheel having a laterally-projecting rim on both sides, friction-shoes adapted to engage the inner faces of said rim, oscillatory heads on opposite sides of said friction-wheel, inclined arms interposed between said heads and shoes, springs interposed between said arms and projections on said heads, cover-plates attached to said heads, and rings inserted in annular grooves in the inner faces 40 of said cover-plates and provided with inwardly-projecting studs, and pinions journaled in said cover and engaging racks formed in said rings, whereby said shoes are held out of engagement with the rim of said friction-wheel, substantially as and for the purposes set forth.

50 8. The combination, with an intermittent grip for saw-mill set-works, consisting of an internal friction-wheel mounted on the set-shaft, friction-shoes adapted to engage the overhanging rim of said friction-wheel, an oscillatory head and inclined arms interposed between said head and shoes, and springs placed between said arms and projections on said head and tending to move said arms into radial lines, of a setting-lever connected with and arranged to oscillate said head, and means for holding said shoes out of engagement with said friction-wheel, so as to allow the latter to be turned backward, substantially as and for the purposes set forth.

65 9. The combination, with an intermittent

70 grip for saw-mill set-works, consisting of a friction-wheel fixed upon the set-shaft and having a laterally-projecting rim on both sides, oscillatory heads, one on each side of said friction-wheel, friction-shoes adapted to engage the inner faces of said rim, and inclined arms interposed between said head and shoes, of a rock-shaft provided with a 75 setting-lever and a cross-head which is connected with and arranged to oscillate the heads of said intermittent grip alternately in opposite directions, substantially as and for the purposes set forth.

80

10. The combination, with an intermittent grip for saw-mill set-works, consisting of a friction-wheel fixed upon the set-shaft, friction-shoes adapted to engage the rim of said friction-wheel, an oscillatory head, and inclined arms interposed between said head and shoes, of a setting-lever connected with and arranged to oscillate said head, and a friction-driver geared with one of the carriage-axles and arranged to be brought into engagement with the friction-wheel of said grip for the purpose of receding, substantially as and for the purposes set forth.

85

11. The combination, with an intermittent grip for saw-mill set-works, consisting of a 95 friction-wheel fixed upon the set-shaft, an oscillatory head connected with and arranged to be operated by the setting-lever, friction-shoes adapted to engage the rim of said friction-wheel, inclined arms interposed between 100 said head and shoes, and springs interposed between said arms and projections on said head, of a ring connected with said oscillatory head and having inwardly-projecting lugs adjacent to said inclined arms, a pinion 105 meshing with a rack in said ring and provided with a crank-arm, and a lever fulcrumed on the carriage and arranged to engage said crank-arm, turn said ring and thereby hold said shoes out of engagement with said friction-wheel, substantially as and for the purposes set forth.

110

12. The combination, with an intermittent grip for saw-mill set-works, consisting of a friction-wheel fixed on the set-shaft, an oscillatory head connected with and arranged to be operated by a setting-lever, friction-shoes adapted to engage the inner face of the rim of the friction-wheel, and inclined arms interposed between said oscillatory head and said friction-shoes, of a friction-driver geared with one of the carriage-axles and arranged to be moved by the operator into engagement with the periphery of the friction-wheel of said intermittent grip, and a brake strap and 115 lever connected therewith arranged to arrest the movement of said friction-wheel, substantially as and for the purposes set forth.

120

13. An intermittent grip consisting of a friction-wheel having a laterally-projecting rim, 130 friction-shoes adapted to engage the inner face of said rim, an oscillatory head, mechanism interposed between said head and shoes, whereby the latter are forced outwardly by

the forward movement of said head and allowed to recede by the backward movement of said head, and mechanism for holding the shoes out of engagement with said friction-
5 wheel, so as to permit the turning of the latter backward, substantially as and for the purposes set forth.

In testimony that I claim the foregoing as my own I affix my signature in presence of two witnesses.

WILLIAM S. BEEMAN.
